US00D853716S

(12) **United States Design Patent** (10) **Patent No.:** **US D853,716 S**
(45) **Date of Patent:** **** Jul. 16, 2019**

(54) **BAG**

(71) Applicant: **Smith & Nephew, Inc.**, Memphis, TN (US)

(72) Inventors: **Edward Brophy**, Argyll and Burke (GB); **David Chadwick**, Skipton (GB); **Kathryn Ann Leigh**, Saint Petersburg, FL (US)

(73) Assignee: **Smith & Nephew, Inc.**, Memphis, TN (US)

(**) Term: **15 Years**

(21) Appl. No.: **29/582,159**

(22) Filed: **Oct. 25, 2016**

Related U.S. Application Data

(62) Division of application No. 29/492,729, filed on Jun. 2, 2014, now Pat. No. Des. 770,173.

(51) **LOC (11) Cl.** **03-01**

(52) **U.S. Cl.**

USPC **D3/232**; D24/108

(57) **CLAIM**

The ornamental design for a bag, as shown and described.

DESCRIPTION

FIG. 1 is a top, front, and left side perspective view of a bag; FIG. 2 is a top, rear, and right side perspective view of the bag of FIG. 1.

FIG. 3 is a front view of the bag of FIG. 1.

FIG. 4 is a rear view of the bag of FIG. 1.

FIG. 5 is a left side view of the bag of FIG. 1.

FIG. 6 is a right side view of the bag of FIG. 1.

FIG. 7 is a top plan view of the bag of FIG. 1; and,

FIG. 8 is a bottom plan view of the bag of FIG. 1.

The broken lines shown represent environmental structure or portions of the bag that form no part of the claimed design.

1 Claim, 7 Drawing Sheets
